United States Patent

Des. 238,037

Patented Dec. 16, 1975

238,037

COFFEE TABLE

Donald B. Gold, San Rafael, Calif., assignor to K.I.S.S.
Industries, Inc., San Rafael, Calif.

Filed Sept. 3, 1974, Ser. No. 502,603

Term of patent 14 years

Int. Cl. D6—03

U.S. Cl. D6—147

FIG. 1.

FIG. 2.

FIG. 1 is a front and top perspective view of a coffee table embodying my new design; and

FIG. 2 is a back and bottom perspective view thereof.

I claim:

The ornamental design for a coffee table, substantially as shown.
